UNITED STATES PATENT OFFICE

2,416,147

BOTTLE CRATE

Sanford J. Blackwell, St. Louis, Mo.

Application January 4, 1944, Serial No. 516,963

4 Claims. (Cl. 217—19)

1

This invention relates to bottle crates.

An object of this invention is to provide a crate for bottles which is so constructed and arranged that it may be readily stacked and may be used for not only holding bottles in a delivery vehicle, but also for holding bottles in a cooler.

A crate constructed according to this invention is provided with a skeleton frame construction having closure members about the sides and ends so that the cold will be retained within the crate. In this manner the crated bottles may be placed in a refrigerator, and when placed in a delivery vehicle the closed walls of the crate will retain the coolness so that the material, such as milk, cream or the like, in the bottles will not deteriorate before delivery.

Another object of this invention is to provide an improved liner for a bottle crate which will constitute a heat insulating means for insulating the contents of the crate.

Another object of this invention is to provide a bottle crate which is formed of a skeleton frame and closure means for closing the sides and ends of the frame.

A further object of this invention is to provide in combination with a bottle crate or carrier, an insulating liner adapted to engage about the interior of the side and end walls, the liner being formed of fibrous sheets, such as cardboard or the like.

A further object of this invention is to provide as a new article of manufacture, a liner construction for bottle crates or carriers which includes relatively stiff sheets of cardboard formed with scored opposite ends so that the ends of the sheets may be bent around the corners of the crate or carrier, and the adjacent ends of adjacent sheets are disposed in overlapping relation so as to provide a tight seal.

A further object of this invention is to provide a crate or carrier which may be easily stacked in firm columns.

To the foregoing objects and others which may hereinafter appear, the invention consists of the novel construction, combination and arrangement of parts as will be more specifically referred to and illustrated in the accompanying drawings, wherein are shown embodiments of the invention, but it is to be understood that changes, variations and modifications may be resorted to which fall within the scope of the invention as claimed.

In the drawings:

Figure 1 is a perspective view of a bottle crate constructed according to an embodiment of this invention.

2

Figure 2 is a bottom plan of the crate,

Figure 3 is a top plan partly in horizontal section of the crate,

Figure 4 is a sectional view taken on the line 4—4 of Figure 3,

Figure 5 is a fragmentary sectional view taken on the line 5—5 of Figure 3,

Figure 6 is a perspective view of the liner embodied in this invention,

Figure 7 is a fragmentary sectional view taken substantially on the line 7—7 of Figure 4,

Figure 8 is a fragmentary horizontal section of the lower portion and one corner of the crate,

Figure 8a is a fragmentary sectional view taken on the line 8a—8a of Figure 8,

Figure 9 is a fragmentary top plan of the bottom forming structure,

Figure 10 is a sectional view taken on the line 10—10 of Figure 9,

Figure 11 is a fragmentary sectional view taken on the line 11—11 of Figure 3,

Figure 12 is a detail side elevation partly broken away and in section of a modified form of this invention,

Figure 13 is a sectional view taken on the line 13—13 of Figure 12, and

Figure 14 is a fragmentary sectional view taken on the line 14—14 of Figure 12.

Referring to the drawings, and first to Figures 1 to 11 inclusive, the numeral 15 designates generally the skeleton frame of a crate designed for holding bottles, such as milk bottles, beer and beverage bottles, or the like. The frame includes an upper rectangular frame member 16 which is formed of opposite side bars or strips 17 and end bars or strips 18. The frame structure also includes lower frame members 19 and 20, the frame members 19 being lower side frame members, and the frame members 20 being lower end frame members. The upper and lower frames are connected together by upright supporting members which include upright corner posts 21, 22, 23 and 24. The upper ends of the corner members 21 to 24 are secured as by rivets 25 to the upper frame 16 and are secured as by rivets 26 to the lower frame comprising the side and end frame members 19 and 20.

Right angular inner corner members 27 are disposed between adjacent side and end members 17 and 18 and the rivets or fastening members 25 extend through the reinforcing angle members 27. An outer L-shaped or right angular bracing member 28 engages about the outer sides of the corner members 21 to 24 inclusive and are secured to the corner members and to the upper frame by

50
55

the rivets or fastening members 25. Lower right angular or L-shaped members 29 engage about the lower posts 21 to 24, inclusive and are secured to the lower frame members 19 and 20 by the rivets or fastening members 26. The lower reinforcing members 29 engage the outer sides of the corner members 21 to 24 and engage on the outer sides of the frame members 19 and 20.

The lower ends of the uprights 21 to 24 are rabbeted as at 30 forming a reduced extension 31 engaging on the inner sides of the lower frame members 19 and 20 so that the fastening members 26 will tightly hold the upright corner members against the inner sides of the lower frame construction. Inner angled corner members 32 are disposed on the inner side of the crate in the lower portion thereof and engage on one leg thereof against the inner side of the reduced extensions 31 of the corner posts. Intermediate uprights 33 are disposed at the sides of the crate being secured as by fastening members 34 to the outer sides of the upper side members 17 and secured as by fastening members 35 to the lower side frame members 19. The lower ends of the intermediate members 33 are rabbeted as indicated at 36 in Figure 4, thereby forming a reduced extension 37 which engages on the inner faces of the lower side members 19.

As shown in Figure 4, the upper frame is provided with a shoulder or rabbet 38 below the upper end thereof and the upper ends of the side members 33 engage against the rabbet 38 and thereby provide a support for the upper frame 16. The upper frame 16 has a substantial portion thereof projecting above the upper ends of the corner members 21 to 24 and the side members 33 so that these crates may be stacked one upon the other, the upper frame 16 providing means at the upper ends of the crates whereby the lower end of a succeeding crate may partly telescope a lower crate.

With a construction of this kind the conventional projecting corner pieces heretofore used in crates of this type will be eliminated.

The outermost intermediate members 39 are disposed in edge abutting relation to the corner members 21 to 24 and the upper and lower bracing members 28 and 29 overlap the outermost intermediate members 29, as shown more clearly in Figure 1. The corner members 21 to 24 inclusive are formed with concave inner side portions 40 and the outermost members 39 are also formed with concave inner portions 41 so that bottles may be disposed within the crate closely adjacent the corners thereof, the concave inner side portions 40 and 41 providing clearance for the large body portions of the bottles. The lower ends of the outermost members 39 as shown in Figure 8 have a reduced extension 42 engaging on the inner sides of the lower side members 19 and the lower end members 20.

In order to provide an additional bracing member at the corners of the crate in the lower portion thereof, I have provided an elongated bracing strap 43 which is interposed between the extension 42 and the inner sides of the lower frame members 19 and 20 and has one of the fastening members 26 engaging therethrough. At each end of the crate there are positioned a pair of upright intermediate members 44 and 45 which are provided with confronting cutouts 46 and 47 adjacent their upper end portions so as to form a hand hold whereby a hand may be readily extended in the space between the cutouts 46 and 47 for grasping the end frame members 18. The

upper ends of the intermediate end members 44 and 45 are secured to the upper end members 18 of the frame 16 by fastening members 48. The lower ends of the end members 44 and 45 as shown in Figure 5 are rabbeted as at 49, thereby providing a reduced extension 50 engaging on the inner sides of the end members 20, and the extensions 50 secured to the end members 20 by fastening members 51.

The skeleton frame structure hereinafter described is adapted to be closed on the sides and ends thereof and in closing the sides of the frame structure, I have provided closure members 52 which engage between the intermediate members 33 and the outermost members 39. These closure members 52 are beveled as at 53 and 54 at their upper and lower ends and on the outer sides thereof and are preferably inclined to the vertical, their lower ends being outermost so that the closure members 52 will not interfere with the larger body portions of the bottles positioned within the crate. The closure members 52 are supported on upper and lower rods 55 and 56 which are extended horizontally through the closure members 52 and are also extended horizontally through the intermediate members 33 and 39 and adjacent corner members.

The opposite ends of the frame structure are closed by inclined closure members 57 and by a relatively short closure member 58. The short closure member 58 extends between the intermediate members 44 and 45 and is of a length to extend from the cutouts 46 and 47 to the upper edges of the end member 20. The closure members 57 and 58 are mounted on a pair of supporting rods 59 and 60 which extend through the closure members 57 and 58 and also through the intermediate end members 44 and 45 and adjacent corner members.

The lower edges of the lower frame members 19 and 20 are protected or shielded by means of metal runners 61 which are of substantially U-shape and these runners or guard members have a relatively long outer leg 62 which at its upper end is provided with an inwardly projecting extension 63 engaging in a horizontal slot 64 formed in the outer sides of the side and end members 19 and 20, respectively.

The corner members 21 to 24 inclusive are also shielded by means of U-shaped guard members 65 which have a relatively long outer leg 66 terminating in an inwardly projecting extension 67. The corner members 21 to 24, inclusive, are formed with a vertical slot 68 within which the extension 67 is adapted to engage. The extension 67 holds the guard member 65 against lateral movement with respect to a corner member, it being understood that each guard member is slipped on the corner member during the assembly of the crate.

The frame structure 15 also includes a pair of spaced apart dividers 69 and 70. The dividers or partitions 69 and 70 at their outer ends abut against the end uprights 44 and 45, respectively, and are secured relative to the end uprights by means of dowels 71. The dividers or partitions 69 and 70 are of like construction and are each formed with oppositely disposed lengthwise spaced apart concave recesses 72 and 73 providing additional space for receiving bottles for holding the bottles against movement lengthwise of the crate.

Upper and lower pairs of transversely extending partition rods 14 and 75 extend through the dividers or partitions 69 and 70 and are mount-

ed in inwardly opening sockets 76 and 77, respectively, which are formed in the intermediate upright frame members 33. The rods 74 and 75 cooperate with the dividers 69 and 70 in forming the desired bottle receiving chambers within the lower portion of the crate. A plurality of pairs of transversely extending bottom forming rods 78 and 79 are disposed transversely across the lower portion of the crate frame and the rods 78 and 79 at their outer ends are extended through the lower side members 19. The bottom forming rods 78 and 79 are positioned below the dividers 69 and 70, and each pair of rods 78 and 79 engages through the upwardly opening slots 80 and 81 which are formed in a pair of elongated strips 82 and 83, respectively, which are positioned against the lower edges of the dividers 69 and 70.

The rods 78 and 79 overlap each other at their inner ends in the slot 81 and as shown in Figure 10 the rod 78 is formed with a down-turned end portion 84 which engages in a hole 85 formed in the supporting strip 83. The inner end of the rod 79 is bent downwardly at right angles as indicated at 86 and the right angular extension 86 engages in an opening 87 formed in the strip 83. The strips 82 and 83 at the opposite ends thereof are beveled off as indicated at 88 and 89, respectively, so that these crates may be used on an endless conveyor and the strips 82 and 83 may provide runners engageable with the conveyor. The beveled end portions 88 and 89 also form spaces 90 between the ends of the strips 82 and 83, and the adjacent end members 20 so that the upper frame or rim 16 of a lower crate may telescope into the bottom of an upper crate.

The longitudinal strips 82 and 83 are held against the dividers 69 and 70 by means of U-shaped straps or clips 91 which have the bights 92 thereof engaging in transverse slots 93 formed in the longitudinal strips and the parallel legs 94 of the supporting clips are formed with openings 95 through which the lower rods 75 extend.

Referring now to Figures 12, 13 and 14, there is disclosed a modified form of this crate which is identical with the crate shown in Figure 1 with the exceptions hereinafter set forth. The crate shown in Figures 12, 13 and 14 includes an upper frame structure 16a similar in every detail to the frame 16, corner forming members 21a similar to the corner members 21 to 24, inclusive, and a bottom frame structure including bottom frame members 19a and 20a. Intermediate vertical frame members 33a are disposed along the sides of the frame structure and end members similar to end members 44 and 45 will be used with the frame structure 15a.

The sides and ends of the frame structure 15a are closed by means of vertically disposed metal plates 96 which engage in confronting vertical slots 97 formed in the intermediate members 33a and the outermost members 39a and adjacent corner members. The lower members of the closure plates 96 rest on the lower frame members 19a and 20a and the upper ends of the plates are provided with inwardly projecting flanges 98 as shown in Figure 13. The inner end of the flange 98 engages below the shoulder 38a which is formed in the outer side of the upper frame 16a. In other respects the crate shown in Figures 12, 13 and 14 is identical with the crate shown in Figures 1 to 11, inclusive.

Referring now to Figure 8 it will be noted that the reinforcing strip 43 is extended inwardly from

the end of the crate and overlaps the lower portion of the extension 31 of an adjacent intermediate upright 33. The lowermost transverse partition rod 75 is extended through the inner end of the strap 43 so as to cooperate with the outermost rivet 26 in holding the strap 43 against endwise movement. The lower frame members 19 and 20 on their inner sides are formed with inwardly projecting flanges 99 as shown in Figure 8a and the lower ends of the extensions 31 and 37 of the uprights 21 to 24, 33 and 39 engage on the upper sides of the flanges 99.

The crate hereinbefore described is adapted to be additionally insulated by means of a fibrous liner generally designated as 100. The liner 100 comprises opposite side members 101 and opposite end members 102. The side members 101 at the opposite vertical edges thereof are provided inwardly from the vertical edges with a pair of parallel scores 103 and 104. The scores 103 and 104 provide a means whereby the opposite vertical edges of the side members 101 may be bent around the corners of the crate.

The side members 101 are also formed adjacent their lower edges with upwardly extending slots 105 whereby the side liner members 101 may be slipped downwardly over the partition rods 74 and 75. Preferably, the lower ends of the slots 105 are flared outwardly and downwardly as at 106. The end liner members 102 are adapted to extend across the ends of the crate and the opposite ends of the liner members 102 are formed with pairs of vertical scores 107 and 108 whereby the opposite ends of the end liners may be bent around the corners in overlapping relation with respect to the bent end portions of the side liners as shown more clearly in Figure 6. In this manner when the side and end liners are in position, there will be provided a tight seal between adjacent side and end liners so as to prevent warm air or the like from entering the interior of the crate. The end liners 102 at their lower edges are formed with upwardly opening slots 109 which are wide enough to permit the end liners 102 to be extended downwardly over the longitudinal dividers 69 and 70. The lower ends of the slots 109 are flared outwardly, as at 110 to facilitate the positioning of the liners.

In the use of this crate the filled bottles may be placed in the several compartments formed by the transverse rods 74 and 75 and the longitudinal dividers 69 and 70. The crate or carrier is of sufficient height so that the tops of the bottles will not project thereabove. The bottoms of the bottles will rest on the bottom forming rods 78 and 79. When the filled crates are placed in cold storage, the liner 100 may be eliminated or removed so that the cold air may more readily contact with the bottles. The crates may be stacked one upon the other, the projecting portion of the upper frame 16 of a lower crate engaging in the interior of the lower frame formed by the bottom members 19 and 20 of a succeeding crate and in the spaces 90 between the ends of the longitudinal strips 83.

When the crates are taken out of cold storage for delivery, the liner 100 may be inserted by slipping the end members 102 in position and bending the opposite ends of the end members 102 around the adjacent corners of the crate. The side members 101 may then be slipped in position with the opposite ends of the side members 101 bent around the corners and interiorly of the bent portions of the end members 102. The liner 100 will thereupon provide an addition-

al insulating means in addition to the closures 52, 57 and 58 for insulating the bottles so that the coolness of the bottles will be retained for a longer period.

By forming the crate with the closure pieces 52, 57 and 58, these pieces may be made out of wood substantially lighter in weight and of less strength than the skeleton frame. In this manner the entire crate will weigh less than would be the case if the crate were made out of the same kind of wood which is normally a fairly hard and tough wood. In other words, the closure pieces may be made out of gum, poplar or similar soft wood, whereas the skeleton frame 15 may be made out of hickory, ash or similar hard and tough wood.

The crate hereinbefore described may also be made either entirely or partly out of metal and also out of plastic either partially or entirely, or a combination of wood, metal and plastic.

This crate has been designed for withstanding rough handling so that it will last for an exceedingly long period of time and will accomplish the purpose for which it has been designed during its entire life. The liner while designed for insertion within the crate hereinbefore described may also be used with other types of crates or carriers, such as wire crates or carriers for insulating such crates or carriers.

The liner will not only act as an insulating medium to keep the bottles cold when removed from cold storage, but in cold weather the liners may be retained in the crates while the latter are on the delivery vehicle so as to keep the bottles from freezing. The liners also constitute a sanitary medium as they keep dirt and other foreign matter from entering the sides and ends of the crates.

It will be understood that the top of the uppermost crate of a stack, or the top of a single crate may be closed by means of a rectangular plate which may be made out of cardboard, fiberboard, metal, wood or any other sheet material either rigid, flexible or partially rigid.

While at this time the liner is designed to be made out of cardboard, fiberboard or the like, it will be understood that the liner may be made out of rubber, rubber composition, either natural or synthetic or out of any suitable material.

What I claim is:

1. A bottle crate comprising a skeleton frame comprising upper and lower rectangular frame members, spaced uprights secured between said frame members, a pair of longitudinal dividers in said frame, pairs of transversely extending compartment forming bars extending through said dividers and embedded in certain of said uprights, and pairs of bottom forming bars extending transversely of said frame and embedded in said lower frame member said lower frame member having lengthwise channels in the outer sides and ends thereof, U-shaped runners engaging over the lower edges of said lower frame member, and a flange carried by each runner engaging in a channel to thereby hold said runner in applied position.

2. A bottle crate comprising a skeleton frame comprising upper and lower rectangular frame

members, spaced uprights secured between said frame members, a pair of longitudinal dividers in said frame, pairs of transversely extending compartment forming bars extending through said dividers and embedded in certain of said uprights, pairs of bottom forming bars extending transversely of said frame and embedded in said lower frame member, closure members disposed between the spaces of said uprights and pairs of longitudinal rods extending through said uprights and said closure members for supporting the latter.

3. A bottle crate comprising a skeleton frame comprising upper and lower rectangular frame members, angled bracing members for said frame members, spaced uprights secured between said frame members, a pair of longitudinal dividers in said frame, pairs of transversely extending compartment forming bars extending through said dividers and embedded in certain of said uprights, and pairs of bottom forming bars extending transversely of said frame and embedded in said lower frame member said lower frame member having lengthwise channels in the outer sides and ends thereof, U-shaped runners engaging over the lower edges of said lower frame member, and a flange carried by each runner engaging in a channel to thereby hold said runner in applied position.

4. A bottle crate comprising a skeleton frame comprising upper and lower rectangular frame members, pairs of inner and outer angled bracing members for said frame members, spaced uprights secured between said frame members, a pair of longitudinal dividers in said frame, pairs of transversely extending compartment forming bars extending through said dividers and embedded in certain of said uprights, and pairs of bottom forming bars extending transversely of said frame and embedded in said lower frame member said lower frame member having lengthwise channels in the outer sides and ends thereof, U-shaped runners engaging over the lower edges of said lower frame member, and a flange carried by each runner engaging in a channel to thereby hold said runner in applied position.

SANFORD J. BLACKWELL.
